Refa, "Refa CAXA M1", Dec. 3, 2019. http://www.refa.net/en/item/refa_caxa_m1/. Shown on p. 1. (Year: 2019).*Primary Examiner — Cynthia Ramirez*Assistant Examiner* — Michael A Maharajh(74) *Attorney, Agent, or Firm* — Sughrue Mion, PLLC(57) **CLAIM**

The ornamental design for a massaging tool, as shown and described.

DESCRIPTION

FIG. 1 is a perspective view of a massaging tool showing my new design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The broken lines illustrate portions of the massaging tool and form no part of the claimed design.

The dash dotted lines denote the boundaries of the claim and form no part of the claimed design.
